CLAIM

The ornamental design for a folding cat hut as shown and described.

DESCRIPTION

FIG. 1 is a perspective view of the folding cat hut in an unfolded position.

FIG. 2 is a top view of the folding cat hut in an unfolded position.

FIG. 3 is a bottom view of the folding cat hut in an unfolded position.

FIG. 4 is a right side view of the folding cat hut in an unfolded position.

FIG. 5 is a left side view of the folding cat hut in an unfolded position.

FIG. 6 is back view of the folding cat hut in an unfolded position.

FIG. 7 is a front view of the folding cat hut in an unfolded position.

FIG. 8 is a perspective view of the folding cat hut in a folded position.

FIG. 9 is a front view of the folding cat hut in a folded position.

FIG. 10 is a back view of the folding cat hut in a folded position.

FIG. 11 is a right side view of the folding cat hut in a folded position.

FIG. 12 is a left side view of the folding cat hut in a folded position.

FIG. 13 is top view of the folding cat hut in a folded position; and,

FIG. 14 is a bottom view of the folding cat hut in a folded position.
